(57) **CLAIM**

The ornamental design for a computer case, as shown and described.

DESCRIPTION

FIG. 1 is an elevational view of a computer case;
FIG. 2 is an enlarged view taken from line 2 in FIG. 1; and,
FIG. 3 is an enlarged perspective view taken from line 3 in FIG. 1.

The broken line showing of portions of the computer case in the figure is included for the purpose of illustrating environmental structure and forms no part of the claimed design.
